[57] CLAIM

The ornamental design for an electric utility meter, as shown and described.

DESCRIPTION

FIG. 1 is right front perspective view of our new design for an electric utility meter;

FIG. 2 is a back elevational view of the electric utility meter of FIG. 1;

FIG. 3 is a right side view of the electric utility meter of FIG. 1;

FIG. 4 is a left side view of the electric utility meter of FIG. 1;

FIG. 5 is a front view of the electric utility meter of FIG. 1; FIG. 6 is a rear view of the electric utility meter of FIG. 1; and,

FIG. 7 is a top elevational view of the electric utility meter of claim 1.

In FIGS. 1 through 7, the broken lines showing of portions of the surface detail, the bottom support structures, the security interlocks, and the current blades, is for illustrative purposes only and forms no part of the claimed design.
